(57) **CLAIM**

The ornamental design for a baseboard covering device, as shown and described.

DESCRIPTION

FIG. 1 is a front perspective view of a baseboard covering device showing my new design;

FIG. 2 is a rear perspective view thereof;

FIG. 3 is a front view thereof;

FIG. 4 is a left side view thereof, the right side view being a mirror image of the left side view;

FIG. 5 is a top view thereof;

FIG. 6 is a bottom view thereof;

FIG. 7 is a rear view thereof;

FIG. 8 is another perspective view thereof, showing the baseboard covering device in an environment of use;

FIG. 9 is another perspective view thereof, showing the baseboard covering device in an environment of use; and, FIG. 10 is a right side view thereof, showing the baseboard covering device in an environment of use.

The broken lines in FIGS. 1, 2, 4, and 7 through 10 represent environmental subject only and form no part of the claimed design.
